PROTECTIVE DEVICE FOR TYPEWRITER ATTACHMENTS FOR MAKING MULTIPLE COPIES

Charles Gordon Rice, Fort Lauderdale, Fla.

Application July 17, 1948; Serial No. 39,333

7 Claims. (Cl. 197—153)

1

This invention relates to attachments for typewriters for making multiple copies by the use of ribbon strips, and more particularly to protective means for use in connection therewith.

In making duplicate copies on the typewriter, sheets of carbon paper are usually employed, and it has been proposed heretofore to use a ribbon strip or strips which are positioned between the sheets of paper in the machine and in the writing area thereof, in order to make the duplicate copies. These ribbon strips have been made of paper or cloth, and the latter are generally inked, similar to the main or usual typewriter ribbon.

One of the difficulties encountered with such arrangements is that the auxiliary ribbon or ribbons may be dragged out of position by the paper as the platen is turned to feed the paper up or down, or however the paper is moved past the writing position. As the auxiliary ribbon or ribbons drift out of position, the duplicate copy may become incomplete.

Another of the difficulties encountered, at least in those forms where the supplemental ribbon strip is caused to move transversely of the writing position so as to present "fresh" areas thereof along the writing line, is that the supplemental ribbon might smudge the pages between which it moves.

It has been proposed in the past to employ protective devices in the form of one or two wires paralleling the portion of the ribbon strip exposed along the writing line, and in some instances these wires have been somewhat greater in diameter than the thickness of the ribbon. Such prior arrangements have been inadequate, and not continually effective.

It is an object of this invention to provide a simple, economical, and effective pair of protective devices, and means to maintain the same under spring tension, so that they are always taut.

It is another object of this invention to provide new and improved arrangements for mounting and maintaining protective wires, or the like, in position.

Still other objects and advantages of my invention will be apparent from the specification.

The features of novelty which I believe to be characteristic of my invention are set forth with particularity in the appended claims. My invention itself, however, both as to its fundamental principles and as to its particular embodiments, will best be understood by reference to the specification and accompanying drawings, wherein the parts of the attachment of general interest

2

are shown in dot and dash lines, and in which—

Fig. 1 is a partial plan view of the typewriter attachment according to my invention, and in which other parts are broken away to facilitate an understanding of the invention;

Fig. 2 is a front elevation of the attachment, parts also being broken away;

Fig. 3 is a section on the line 3—3 of Fig. 2;

Fig. 4 is an end elevation looking toward the 10 left hand end seen in Figs. 1 and 2;

Fig. 5 is an enlarged fragmentary end view of the lower half of the ribbon guide or wire support;

Fig. 6 is a section on lines 6—6 of Fig. 2;

Fig. 7 is a front elevation of the part shown in 15 Fig. 6;

Fig. 8 is an end view of the spring tensioning element;

Figs. 9 and 10 are views similar to Fig. 7 of 20 modifications of my invention, and

Figs. 11 and 12 are fragmentary detail views of a modified form of a wire holding means.

In the embodiments of the invention herein described, the mechanism is made in the form of 25 an attachment to be mounted on any standard typewriter, without requiring changes in its construction, and is so arranged that the attachment may or may not be used for making duplicate copies by moving the supplemental ribbon 30 in or out of writing position.

The attachment comprises a pair of arms 11 and 12, joined together by a tube 13 so as to pivot as a unit, the arms 11 and 12 being mounted on the left and right ends of the typewriter carriage, and the tube 13 being at the rear thereof. The tube 13 is pivotally mounted so that the arms may be swung to an upright position, and the typewriter may be used to make single copies, or multiple copies by use of carbon sheets.

35 The arms 11 and 12 carry ribbon spools 14 and 15, respectively, on which the supplemental ribbon is mounted. Mechanism is provided for driving the spools to move the ribbon, but since this invention is not concerned with such mechanism, it is not shown or described in detail.

40 Mounted upon the left hand arm 11 I provide a ribbon guide 16, and upon the right hand arm 12 a second ribbon guide 17. The guide 16 is provided with a horizontal slot 18, and a second slot 19 at an angle of 45° with the horizontal slot. Arm 17 has a similar horizontal slot 21, and a 45° slot 22, the slot 22 also being disposed at 90° with slot 19. In operation, the ribbon comes from spool 14, passes outwardly through slot 18, inwardly through slot 19, thence behind

the ribbon guide 16, across the face of the platen, behind the rear face of ribbon guide 17, thence through slots 22 and 21, and on to the other spool 15.

The protective devices, with which this application is concerned, are carried by the ribbon guides 16 and 17. These comprise wire strands 31 and 32 spaced apart vertically by a distance a little greater than the width of the supplemental ribbon which passes between them, and are somewhat larger in diameter than the thickness of the ribbon. I have found that satisfactory results are obtained with what is known as #38 gage music wire (.008" diameter), and the wires are spaced apart one-half inch, when using a ribbon three-eights of an inch wide and about .004" or .005" thick, but I do not wish to be limited either to these sizes or the stated ratios.

To mount and hold the wires 31 and 32 in position, I may provide a pair of holes 33 and 34 in the side face of ribbon guide 16, these holes being slightly larger in diameter than the wires employed, and located at spaced points on an arc substantially concentric with the typewriter platen.

In the embodiment of the invention now being described, the wire strands are formed from a single piece bent into an elongated U-shape, and if desired, I may provide entrance slots 35 and 36 for the holes 33 and 34, to facilitate mounting the wire in ribbon guide 16, and a clamping finger 37 struck up from the ribbon guide 16, and which may be bent down over the wire to hold it, after the wire is put in position.

The wire strands extend behind the spaced apart ribbon guides 16 and 17, through holes in ribbon guide 17 similar to holes 33 and 34, and have the open end of the U secured at the right hand side of the carriage by means of a tensioning spring arrangement 41, which is mounted on ribbon guide 17. The spring 41 is preferably a formed strip, which is arcuate to somewhat conform to the shape of the platen, and has a flat center portion 40, diverging angularly extending portions 42 and 43, and outwardly extending wire carrying portions 44 and 45. The latter portions are provided with holes through which the ends of the wire are threaded, the end being knotted with the spring placed under tension to exert the desired tension on the wires.

The center portion 40 has spring ears 46 and 47 extending from and perpendicularly to opposite sides of the center portion. To assemble the spring 41 on ribbon guide 17, a slot 48 is provided in the side face of the ribbon guide, which slot is just large enough to slidably receive ear 47, while ear 46 engages the front of the ribbon guide. The ears form a clip which with the slot 48 keep the spring mounting from wobbling.

As noted, in the embodiment of the invention just described, strands 31 and 32 are actually one continuous wire, but it will be understood that this is not necessarily required, as they may be separate strands each individually mounted, as shown at 49 and 50 in the modification of Fig. 9. In this embodiment, the wires are simply threaded through holes in the side flanges of ribbon guides 16 and 17, and knotted or otherwise headed to hold them in position. In this figure, no springs are shown but spring tension may be maintained on the wires by giving the arms 11 and 12 a slight outward bias or spring, and then pulling them inward to be parallel while knotting the wires 49 and 50. Thus, the resiliency of arms 11 and 12 would serve to maintain the wires under tension.

In the embodiment shown in Fig. 10, still another method is used to maintain tension in the wires. In this instance, wires 51 and 52 have their right hand ends formed into coiled spring portions 51a and 52a, which bear against the side of ribbon guide 17. The wires are assembled in holes in the ribbon guides 16 and 17 with the portions 51a and 52a under compression, and since the wires are slidable in the holes, these spring portions serve to keep the wires 51 and 52 under tension.

Referring now to Figs. 11 and 12, I have shown a modification of the method of mounting the protector wires on ribbon guide 16. In this instance the side of guide 16 is provided with a wire receiving hole 53, which may or may not be of the same diameter as the wire, and a slit or cut 54 is provided from the edge of the guide into the hole 53. The lower portion 55 may be slightly bent out of position, as shown in Fig. 12, the wire inserted, and the portion 55 bent back to its original position, and may clamp the wire strand.

It will be seen that with the wire strands paralleling the edges of the portion of the ribbon which stretches between the ribbon guides, should this portion of the ribbon tend to creep with the paper as it is moved past the writing line of the platen it will encounter the particular wire and be stopped. The fact that the wire is slightly larger than the thickness of the ribbon tends to reduce the friction of the paper on the ribbon; and the whole arrangement protects the papers from being smudged by the supplemental ribbon, even along the edges of the sheets. The continual tensioning of both wires protects them from damage and dislodgment in case they are accidentally struck, and also provides a take-up for any incidental stretching of the wires or either of them. Finally, the simple mounting arrangement provides economical initial manufacture and inexpensive servicing and repairs in the field.

In the specification, I have explained the principles of my invention and the best mode in which I have contemplated applying those principles, so as to distinguish my invention from other inventions; and I have particularly pointed out and distinctly claimed the part improvement or combination which I claim as my invention or discovery.

While I have shown and described certain preferred embodiments of my invention, it will be understood that modifications and changes may be made without departing from the spirit and scope thereof, as will be clear to those skilled in the art.

I claim:

1. In mechanism of the class described having a pair of ribbon guides adapted to be disposed forwardly of and adjacent the ends of a platen of the machine to which the mechanism is applied, a pair of vertically spaced wires extending between said ribbon guides, and a spring located between said wires and the outer edge of at least one of said ribbon guides for maintaining said wires under tension.

2. In mechanism of the class described having a pair of arms adapted to be disposed adjacent the ends of a platen of the machine to which the mechanism is applied and a ribbon extending between said arms, a pair of vertically spaced elements carried by said arms and parallel to edge portions of said ribbon, and a spring having oppositely extending portions mounted on one of 70 said arms, the ends of said elements being se-

cured thereto for maintaining said elements under spring tension.

3. In mechanism of the class described having a pair of ribbon guides adapted to be disposed adjacent opposite ends of a platen of the machine to which the mechanism is applied, a pair of wire strands secured to one of said ribbon guides, and a spring carried by the opposite ribbon guide and having two projecting portions, the free ends of said wire strands being secured in said portions whereby to place the strands under tension.

4. In mechanism of the class described having a pair of ribbon guides adapted to be disposed adjacent opposite ends of a platen of the machine to which the mechanism is applied, a pair of wire strands secured to one of said ribbon guides, and a spring carried by the opposite ribbon guide and having a central flat portion engaging the ribbon guide and outwardly extending spring portions, the free ends of the wire strands being secured in said outwardly extending portions.

5. In mechanism of the class described having a pair of ribbon guides adapted to be disposed adjacent opposite ends of a platen of the machine to which the mechanism is applied, a pair of wire strands extending between the ribbon guides, and a spring mounting on one of the ribbon guides and receiving said wire strands, the spring mounting comprising a mounting clip engaging the ribbon guide and a pair of projecting spring arms to which the wire strands are respectively attached.

6. In mechanism of the class described having a pair of ribbon guides adapted to be disposed

adjacent opposite ends of a platen of the machine to which the mechanism is applied, one of said guides having a flange and a slot in said flange, a pair of wire strands extending between the ribbon guides, and a spring mounting on one of the guides and receiving said wire strands, said mounting comprising a central portion having a pair of ears extending therefrom, one of said ears being received in said slot and the other of said ears engaging the surface of said guide, and a pair of projecting spring arms to which the wire strands are respectively attached.

7. In mechanism of the class described having a pair of ribbon guides disposed adjacent opposite ends of a platen of the machine to which the mechanism is applied, each of said guides having a flange and each of said flanges having a pair of spaced mounting holes located therein at points on an arc, wire strands extending between the ribbon guides and received in said holes, and a spring mounting on one of the guides having an arcuate shape substantially coinciding with the arc on which the holes are located and receiving one end of said wire strands.
